Primary Examiner — Christy Nemeth(74) *Attorney, Agent, or Firm* — Innovation Capital Law Group, LLP; Vic Lin(57) **CLAIM**

The ornamental design for a box for battery cells, as shown and described.

DESCRIPTION

FIG. 1 is a top plan view of a box for battery cells, showing my new design;

FIG. 2 is a bottom plan view thereof;

FIG. 3 is a right elevation view thereof;

FIG. 4 is a left elevation view thereof;

FIG. 5 is a rear elevation view thereof;

FIG. 6 is a front elevation view thereof;

FIG. 7 is a top perspective view thereof; and,

FIG. 8 is a bottom perspective view thereof.

The broken lines in the drawings are for the purpose of illustrating portions of the article that form no part of the claimed design.
